Filed Oct. 9, 1973, Ser. No. 404,707

Term of patent 14 years

Int. Cl. D29—02

U.S. Cl. D10—111

FIG. 3

FIG. 4

FIG. 1 is a front isometric view of a bicycle reflector showing my new design;

FIG. 2 is a side isometric view of the reflector;

FIG. 3 is a front isometric view of the reflector with the snap members in clasping position; and

FIG. 4 is a side isometric view of the reflector of the present invention in assembled form.

The cross-hatching which indicates a conventional reflective surface is partially shown in FIGS. 1, 2, 3, and 4 for convenience of illustration, it being understood that the cross-hatching is uniformly continuous over the area indicated.

I claim:

The ornamental design for a bicycle reflector, substantially as shown and described.
